BODY SIDE FRAME

Martin P. Blomberg, Hinsdale, Ill., assignor to
 General Motors Corporation, Detroit, Mich., a
 corporation of Delaware

Application July 1, 1946, Serial No. 680,764

8 Claims. (Cl. 105—396)

1

This invention generally relates to vehicle bodies and more particularly to improvements in body side frames.

The object of the invention is to provide a simple improved arrangement of the chords, posts and diagonals of a welded truss type body side frame which requires a minimum number of side panel mounting members welded to the members forming the truss for reinforcement thereof and for readily attaching the exterior side panels.

The novel form and arrangement of the members forming the welded truss type body side frame and panel mounting and reinforcing members will become apparent by reference to the following detailed description and drawings clearly disclosing one modification of the invention which is particularly adapted for a side frame of the body or cab of a locomotive of the Diesel electric type.

Figure 1 of the drawings is a two part vertical elevation view of the side frame.

Figure 2 is a two part vertical sectional view taken on line 2—2 of Figure 1.

Figures 3, 4 and 5 are vertical sectional views taken, respectively on lines 3—3, 4—4 and 5—5 of Figure 1.

As illustrated in the various figures of the drawings the body or cab side frame assembly is of the truss type comprising built-up upper and lower chord members, generally indicated at 1 and 3, and connected by suitable gussets and stiffening members to the ends of vertical posts and diagonal members of different sectional thickness. These members comprise angle end posts 5 of thin section, H shaped bolster posts 7 and diagonals 9—11 of thicker section adjacent the end posts and intermediate channel posts 13 and diagonals 15 of thinner section.

As best illustrated in Figures 2, 3, 4 and 5, the upper chord member comprises a Z bar 17 and an arcuate closure plate 19 welded thereto to form the hollow upper chord 1 and the arcuate eave portion of the cab roof.

Stiffening members 21 are welded in the hollow upper chord intermediate the ends and these members are provided with flanges in alignment with the webs and flanges of the posts and diagonal members for attachment of the upper ends thereof by welding to the upper chord adjacent the flanges of the stiffening members 21. Carlines 23 of thick section are also welded between the upper chord members 1 adjacent the stiffening members 21 and other carlines 25 and partial carlines 27 of the thinner section are welded at the outer ends to the inside surface of

2

the upper chord 1. Purlines 29 are welded between certain of the carlines at the ends of the side frame to support roof plates and intermediate hatch covers are adapted to be located between these roof sections and another thicker section centrally located carline 23.

The lower chord 3 comprises a Z bar 31 and an angle bar 33 welded along the end of the outer horizontal flange thereof.

10 As best illustrated in Figure 3 the lower end of the inner flange of the bolster post 7 is cut away from the web and bent inwardly and welded directly to and by means of a gusset 35 to a built-up body bolster 37 having upper and lower plates 39—41 which are welded to the upper inner and lower outer horizontal flanges of the Z bar 31 of the lower chord 3. The end of the vertical web portion of the bolster 37 is also welded to the inside of the vertical web of the Z bar 31 and 15 a jacking pad 43 is welded to the lower bolster plate 41 directly below each bolster post 7.

The inner and outer lower end surfaces of the bolster posts 7 and the thicker section diagonals 9—11 are flush with the inner vertical surface 25 of the angle bar 33 and the outer vertical face of the web of the Z bar 31 and these faces are joined by welding and by suitable longitudinal gusset plates welded between these members. The lower end surfaces of the bolster posts 7 30 and diagonals 9—11 are also welded to the upper flange surface of the angle bar 33.

The inner and outer upper end surfaces of the bolster posts 7 and diagonals 9—11 are also flush with the inner vertical surfaces of the web 35 and lower flange of upper chord Z bar 11 respectively and these surfaces are joined by welding and by longitudinal gusset plates welded between these members. The upper ends of the bolster posts 7 and diagonals 9—11 are also 40 welded directly to the horizontal flange of the upper chord Z bar 11 adjacent the stiffening members 21 in the upper chord 1.

The inner surfaces of the upper and lower ends of the intermediate channel posts 13 and diagonals 15 are also flush with the inner surface 45 of the vertical web of the Z bar 11 of the upper chord and with the outer surface of the vertical web of the Z bar 31 of the lower chord 3. The upper ends of the intermediate posts 13 and diagonals are welded to the lower horizontal flange of the Z bar 11 of the upper chord 1 and the inner surfaces of upper ends thereof are welded to longitudinal gusset plates which are also welded to the vertical web of the Z bar 11. The lower ends of the intermediate posts 13 and

diagonals are welded to the upper surface of the angle bar 33 of the lower chord 3 and the lower end inner surfaces thereof abut and are welded directly to the outer face of the vertical web of the Z bar 31 of the lower chord 3 and to longitudinal gusset plates welded therebetween. As the intermediate channel posts 13 and diagonals are of the same sectional thickness and of less thickness than the bolster posts 7 and diagonals 9-11 the outer surfaces thereof are in a plane parallel to and slightly within the plane of the outer surfaces of the bolster posts 7 and diagonals 9-11. The outside lower end surfaces of the intermediate posts 13 and diagonals are welded to longitudinal gusset plates which are also welded to the upper surface of the angle bar 33 of the lower chord 3. The outside upper end surfaces of the intermediate posts 13 and diagonals 15 are also welded to longitudinal gusset plates which are also welded to the horizontal surface of the Z bar 17 of the upper chord 1 adjacent the stiffening members 21 therein.

The outer lower end surface of the angle end posts 5 are welded flush with the outer surface of the diagonals 9 and to longitudinal gussets connected to these diagonals. The upper end of the end posts 5 are welded to the lower horizontal flange of the Z bar 17 of the upper chord 1 and the outer surface of these posts are welded to the inner surface of the lower vertical flange of this Z bar.

It will be evident with the above described arrangement of the truss members that the outer surfaces of the end posts 5 and also the bolster posts 7 and diagonals 9-11 adjacent thereof are in the same plane with the inner vertical surfaces of the lower flange of the upper chord Z bar 17 and angle bar 33 of the lower chord and that the outer surfaces of the intermediate posts 13 and diagonals 15 are in a parallel plane inset with respect thereto.

Upper panel mounting strips 45 are welded along the inside vertical surface of the lower flange of the Z bar 17 of the upper chord and at the ends flush with the outer surfaces of the end posts 5, bolster posts 7 and diagonals 9-11. Lower panel mounting strips 47 are welded along the inner surface of the vertical flange of the angle bar 33 of the lower chord member 3. Combined belt rail reinforcing and panel mounting members 49 of U shape and provided with outwardly extending flanges are welded at the ends flush with the outer surfaces of the end posts 5, bolster posts 7 and diagonals 9-11 and the flanges of the members 49 welded between the two diagonals 11 are also welded intermediate their ends to the outer surfaces of the intermediate posts 13 and diagonals 15, as the thickness of the members 49 are selected for attachment in this manner. The members 49, as best shown in Figures 1, 2 and 3, accordingly form two belt rails parallel to and intermediate the upper and lower chords 1-3 and also serve as reinforcing and panel supporting members as the outer surfaces thereof are in the same plane as the upper and lower panel mounting strips 45-47.

Other horizontal panel mounting strips 51 and vertical panel mounting strips 53-55 are welded flush at the ends between the upper and lower mounting strips 45-47 and between the combined belt rail reinforcing and panel mounting members 49 so that their outer surfaces of all are in the same plane.

The panel mounting strips and members with

this truss form of side frame are few in number and are easily attached in the above described manner to the members forming the truss, and may be drilled and tapped for clamp bolts 51 passing through openings in batten strips, such as shown at 61-63-65 in Figure 2 for readily clamping the horizontal and vertical edges of exterior panels or plates, not shown, to the outer surfaces of the panel mounting strips and members.

I claim:

1. A body side frame including parallel longitudinal members, connecting members secured at the ends therebetween and having the outer surfaces thereof in different planes parallel to the outer edges of said longitudinal members, and other connecting members having the inner and outer surfaces thereof secured flush with the respective outer surfaces of said first mentioned connecting members and provided with removable clamping means for the attachment of outer side panels.

2. A body side frame of the truss type comprising parallel upper and lower chord members, posts and diagonals secured at the ends between said chord members, said posts and diagonals having the outer surfaces thereof in different planes parallel to the outer edges of said chord members and combined reinforcing and side panel mounting members having the inner and outer surfaces thereof secured to the outer surfaces of said posts and diagonal members located in different parallel planes, said panel mounting members having panel clamping means thereon.

3. A body side frame of the truss type comprising parallel upper and lower chord members, end and intermediate posts and diagonals secured at the ends between said chord members, said end and intermediate posts and diagonals having the outer surfaces located in different planes parallel to the outer surfaces of said chord members, panel mounting members having the outer surfaces secured flush with the outer surfaces of said end posts and diagonals and having the inner surfaces secured flush with the outer surfaces of said intermediate posts and diagonals, and panel attaching means carried on the outer surfaces of said panel mounting members for removably attaching panels to the body side frame.

4. A body side frame of the truss type comprising parallel upper and lower chord members, end posts and diagonal members secured at the ends between the end portions of said chord members and having the outer surfaces of said posts and diagonals located in a plane slightly within and parallel to the outer surfaces of said chord members, intermediate posts and diagonal members secured at the ends between the intermediate portions of said chord members and having the inner surfaces in the same plane as the inner surfaces of said end posts and diagonals, the outer surfaces of said intermediate posts and diagonals being located in a plane parallel and within the plane of the outer surfaces of said end posts and diagonals, panel mounting strips secured along the outer edges of said upper and lower chord members and between the end posts and diagonals with the outer surfaces of said strips flush with the outer surfaces of said end posts and diagonals and combined reinforcing and panel mounting members serving as longitudinal belt rails secured intermediate the ends thereof to the outer surfaces of said intermediate posts and diagonals and the outside end surfaces

thereof secured flush with the outer surfaces of said end posts and diagonals, said panel mounting strips and members having panel attaching means thereon for removably attaching panels to the body side frame.

5. A body side frame of the truss type comprising parallel upper and lower chord members, end posts, bolster posts and diagonal members secured between said chord members with their outer surfaces in a plane slightly inside the outer edges of said chord members, horizontal panel mounting strips secured along the outer edges of said chord members and between said end posts, bolster posts and diagonals with the outer surfaces thereof flush with the outer surfaces of said end posts, bolster posts and diagonal members, combined intermediate reinforcing and panel mounting members secured at the ends between said end posts, said bolster posts and said diagonal members with their outer surfaces flush with the outer surfaces thereof and intermediate posts and diagonals connected at their ends between said chord members and having their outer surfaces connected to the inner surfaces of said combined intermediate reinforcing and panel mounting members, said panel mounting strips and members having removable panel clamping means thereon.

6. A body side frame of the truss type comprising parallel upper and lower chord members having inwardly extending vertical outside flanges, end posts, bolster posts and diagonal members secured at the ends and to the inner surfaces of the flanges of said chord members, panel mounting strips secured along the inner surfaces of the flanges of said chord members and secured at the ends flush with the outer surfaces of said end posts, said bolster posts and said diagonals, combined horizontal belt rail and panel mounting members secured at the ends flush with the outer surfaces of said end posts, said bolster posts and said diagonals intermediate the ends thereof, other posts and diagonals secured at the ends between said chord members and intermediate the ends to the inner surfaces of said belt rail members and vertical panel mounting strips secured at the ends between said belt rail members and said first named panel mounting strips flush with the outer surfaces thereof, said panel mounting strips and said combined belt rail and panel mounting members having removable panel clamping means removably supported thereon.

7. A body side frame comprising parallel upper and lower horizontal members, connecting members secured between adjacent ends of said horizontal members, said connecting members having their outer surfaces in a plane parallel to the

outer edges of said horizontal members, horizontal panel mounting strips having their outer surfaces secured along the outer edges of said horizontal members and flush with the outer surfaces of said connecting members and secured therebetween, intermediate horizontal panel mounting members also having their outer surfaces flush with the outer surfaces of said connecting members and secured therebetween and forming parallel belt rails, vertical panel mounting strips having their outer surfaces flush with and secured between said horizontal mounting strips and members and intermediate connecting members having their outer surfaces in the same plane and secured between the intermediate portions of said upper and lower horizontal members and to the inner surfaces of said intermediate horizontal panel mounting members, said panel mounting strips and members having removable panel clamping means thereon.

8. A body side frame of the truss type comprising an upper built-up chord member forming the eave portion of a roof and having a depending outer flange, a lower chord member parallel thereto and having upwardly extending outer and inner flanges, end posts, bolster posts and diagonal members having their outer surfaces secured to the inner surfaces of the outer flanges of said chord members, intermediate posts and diagonal members having their inner surfaces secured to the inner surface of said inner flange of said lower chord member and to said upper chord member so that the outer surfaces of said intermediate posts and diagonal members are in a plane inside and parallel to the outer surfaces of said end posts, said bolster posts and said first mentioned diagonal members and horizontal belt rail members having their inner surfaces secured to the outer surfaces of said intermediate posts and diagonal members and their outer surfaces flush with said first mentioned diagonal members and secured therebetween to form parallel belt rails and panel mounting members, said members having removable panel clamping means thereon.
